UNITED STATES PATENT OFFICE.

JAMES M. PERRY, OF SHARON, PENNSYLVANIA.

PLATE-MILL.

1,159,531.

Specification of Letters Patent.

Patented Nov. 9, 1915.

Application filed April 5, 1913. Serial No. 759,148.

To all whom it may concern:

Be it known that I, JAMES M. PERRY, a citizen of the United States, residing at Sharon, in the county of Mercer and State 5 of Pennsylvania, have invented certain new and useful Improvements in Plate-Mills, of which the following is a specification.

My invention pertains to rolls for use in rolling mills and is directed to a three high 10 plate mill.

The particular objects sought to be accomplished in the present invention embody all those embraced within the application previously filed by myself October 28, 1912, 15 Serial No. 728,319, for an improvement in finishing rolls, with the addition, however, of certain valuable improvements by which my mill may be used for double passing, that is, permitting the passing of the sheet 20 or plate to be rolled through the mill in both directions.

As in the previous application, I utilize the advantages of a small knife roll and prevent the breaking of this small knife roll by 25 having a tread roll to take the back thrust and prevent the knife roll from springing away from the plate. In the present case, during one pass the upper roll takes up the up and back thrust of the knife roll, while in 30 the reverse pass the lower roll takes up the down and back thrust of the knife roll.

In order to accomplish the foregoing, it is necessary that the knife roll have its center position forward of the roll which is to 35 take up the thrust from the knife roll, and the present invention contemplates such a combination of elements, arrangements of parts and specific structural details as will permit of the knife roll being thrown forward relatively to one roll and then forward relatively to the other roll.

In the drawings in which is shown a preferred arrangement of the rolls in accordance with my invention, Figure I is a side elevation of the roll housing showing the rolls therein. Fig. II is a cross sectional view of the structure shown in Fig. I taken on a line passing through the top of the cam member 10, 10' for the purpose of showing the arrangement of the knife roll shift. Fig. III is a front elevation of the rolls as shown in Fig. I. Fig. IV illustrates the arrangement of the rolls when the knife roll has been shifted for a pass between it and the lower roll. Fig. V discloses the same arrangement as shown in Fig. IV with the

knife roll, however, shifted for a pass between it and the upper roll.

Referring now to the several figures in which like reference characters designate like parts, (1) represents the housing; (2) the journal bearing for the knife roll; (3) the bearing for the lower roll; (4) the rider and 4" the bearing for the upper roll. Suitable clamps 4' passing through the rider 5 hold the upper roll to its bearing. The lower, knife and upper rolls are represented by the letters A, B and C respectively. Rolls A and C, which are of equal diameter, are provided with the usual wabblers which 70 by means of boxing, not shown, are connected to the source of power.

(9) represents the plate upon which the rolls act.

At each side of the journal bearing (2) 75 of the knife roll B, I provide a pair of cams (10, 10') which are adapted to partially rotate in the cam seats (11, 11'). These cams are provided at their upper ends with parallel extensions (12, 12'). The extensions (12) 80 are connected by the cross piece (13) while the extensions (12') are similarly connected, so that the rotation of either of the cams (10) or (10') affords a corresponding rotation of the other cam. Extending outwardly from the top of the outer cam (10) and (10') are the arms (14). These arms at their outer ends are connected by the member (15) at the central portion of which is provided a suitable handle. 90

As shown more clearly in Figs. I and II, when the member (15) is drawn toward the right, the cams rotate in a contra-clockwise direction so that the bearing (2) is forced to the right and its right end abuts 95 against the portion 1" of the housing. In this position the center of the roll B is in line with the center of the roll A, as shown by the dotted line Y—Y. The rolls are now in a position for passing the plate between 100 the knife and the lower roll as shown in Fig. IV, in which pass the back and upward thrust of the knife roll B is taken up and opposed by the upper roll C. By reversing the member (15), the cams are rotated in a clockwise direction and the journal bearing (2) of the roll B moves to the left, in which position the line X—X, which passes through the center of the roll C, also passes through the center of the roll B. The 105 rolls are now put in the position as shown in Fig. V, and so positioned are ready to re- 110

ceive a pass from left to right, that is, for the passage of the plate (9) between the knife roll B and the upper roll C. In this position the back and downward thrust of the knife roll is taken up and opposed by the lower roll A.

As is well known in the art, plate mills are provided with screws to raise or lower the rolls. For the purpose of clearness, this 10 very well known element has been omitted from the drawing. It should of course be understood that when the knife roll B is shifted, the upper roll C may be raised by such screws.

15 I have set forth in my prior application the fundamental purpose of employing a small knife roll to obtain a reduction of the plate or sheet to be rolled by means of a small bite, and at the same time by having 20 a relatively large roll on the side of the knife roll opposite to that through which the plate passes, to prevent the small knife roll from breaking, or at least from springing away at the center from the piece, thus 25 giving an uneven gage. As will be readily seen, in the present construction, I have adapted this principle to a two pass mill so that all the advantages sought to be obtained in my prior application, which is directed 30 to a finishing mill, can be obtained in a plate mill. Irrelevant structure and matters of detail, which may be changed to suit the particular conditions under which the mill 35 is to be operated, have been omitted.

35 I claim—

1. In a plate mill, an upper roll and a lower roll having equal diameters, an intermediate roll of smaller diameter and means for shifting the small roll horizontally relative to the larger rolls.

40 2. In a plate mill, an upper roll and a lower roll, the axis of one of said rolls being forward of the other, an intermediate roll and means for shifting said roll to a position in line with either the upper or lower roll.

3. In a three high mill having the upper and lower rolls out of alinement, an intermediate roll adapted to be shifted into alinement with either roll.

4. In a three high mill, the combination of a housing, an upper and lower roll therein, one of said rolls being offset relative to the other, an intermediate roll and means, within the housing, for shifting the latter 55 roll into alinement with either of the other rolls.

5. A plate mill having three rolls, the upper roll being offset relative to the lower roll, a horizontally shiftable intermediate 60 roll, and means for shifting said roll into alinement with either of the other rolls, for the purpose of procuring a pair of reducing rolls in the two rolls so alined, the intermediate roll being at all times in contact with 65 the roll with which it is unalined.

6. In a three high mill, two rolls having laterally immovable bearings and the third roll having laterally shiftable bearings.

7. In a plate mill, the combination of an 70 upper and lower roll having laterally immovable bearings and an intermediate roll having laterally shiftable bearings.

8. In a plate mill, an upper and lower roll mounted in laterally immovable bearings, 75 said rolls being parallel but offset vertically as to each other and an intermediate roll mounted for lateral movement into vertical alinement alternately with the other two rolls.

9. In a three high mill, the combination of an upper and a lower roll with a middle roll, the distance between the upper and lower rolls, taken from the adjacent portions of said rolls, being normally less than 85 the diameter of the intermediate roll.

In testimony whereof I affix my signature in presence of two witnesses.

JAMES M. PERRY.
